(57) **CLAIM**

The ornamental design for a wearable paint brush holder, as shown and described.

DESCRIPTION

FIG. 1 is a front perspective view, shown in a state of use with environment, of a wearable paint brush holder, showing my new design;

FIG. 2 is a front perspective view thereof;

FIG. 3 is a rear perspective view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof; and,

FIG. 9 is a bottom plan view thereof.

The broken lines in FIG. 1 showing a person and a paint roller depict environmental matter that forms no part of the claimed design. The remaining broken lines in the figures depict portions of the wearable paint brush holder that form no part of the claimed design. The dot-dash broken line shows the bounds of the claim and form no part of the claimed design.
